UNITED STATES PATENT OFFICE.

MONTROSS WASHBURN, OF OSSINING, AND ROGER D. GRANGER, OF NEW YORK, N. Y.

FURNACE-GRAVE.

No. 872,869.

Specification of Letters Patent.

Patented Dec. 3, 1907.

Application filed August 22, 1907. Serial No. 389,656.

To all whom it may concern:

Be it known that we, MONTROSS WASHBURN, a resident of Ossining, county of Westchester, and State of New York, and ROGER D. GRANGER, a resident of the city of New York, borough of Brooklyn, county of Kings, and State of New York, both citizens of the United States, have invented new and useful Improvements in Furnace-Grates, of which 10 the following is a full, clear, and exact description.

This invention is an improved furnace grate, the object of which is to provide a construction comprising a plurality of grate sections, each carrying a plurality of pivotally supported grate bars, and an operating means for swinging the grate sections and grate bars on their individual pivots, as desired.

20 The invention further contemplates the provision of means for locking the several grate bars against any relative movement while the grate sections are being swung to and from a dumping position.

25 The invention also resides in certain special features of construction and arrangement of parts which will be fully set forth hereinafter and particularly pointed out in the claims.

30 Reference is to be had to the accompanying drawings forming a part of this specification, in which similar characters of reference indicate corresponding parts in all the views.

35 Figure 1 is a longitudinal vertical section through the fire-box of a furnace with the preferred embodiment of our improved grate applied thereto and showing one of the grate sections swung to a dumping position;

40 Fig. 2 is a side elevation on an enlarged scale of one of the grate sections, the said section being partly in section on the line 2—2 of Fig. 4; Fig. 3 is a sectional view on the line 3—3 of Fig. 4; Fig. 4 is a cross section 45 through one of the grate sections on the line 4—4 of Fig. 2; Fig. 5 is a cross section through one of the operating rods, illustrating the manner in which it is connected and disconnected with one of the grate sections;

50 Fig. 6 is a longitudinal section through the outer end of the operating mechanism; and Fig. 7 is a fragmentary view of the outer portion of the operating mechanism looking in the direction at right angles to Fig. 6.

55 Our invention as shown in Fig. 1 comprises a plurality of grate sections 10, each of

which is provided with a plurality of grate bars 11, the sections being pivotally supported substantially midway their length on trunnions or pivots 12 which are revolubly mounted in notched bearings formed in side frames 13. The grate bars are also pivotally supported on individual pivots or trunnions 14 at opposite ends which rest in notched seats formed in the upper edges of their respective grate sections. These trunnions are covered by the extended ends of the bars, as best shown in Fig. 4, which increases the effective grate area. The sides of each grate section, as best shown in Figs. 3 and 4, are 70 rigidly connected together at the bottom by cross bars 15, and one of the said sides is constructed with inwardly projecting studs 16 which are spaced apart and receive and support a slide 17, the latter being provided with 75 slots 18 at opposite ends for the reception of the studs and intermediate rack-teeth 19 formed on its bottom edge. The slide 17 is also constructed with a plurality of upwardly projecting slotted seats 20, equal in number 80 to the number of grate bars carried by each section, in the present instance shown to be four, and are engaged by studs 21 carried on the lower inner face of depending arms 22 formed integrally with, or otherwise rigidly 85 attached to, the grate bars. That side of each grate section which carries the slide 17 is provided with an inwardly projecting stud 23, preferably arranged between the cross bars 15 near the lower edge of the section, 90 and serves as a pivot for a lever 24, the top arm of which is made in the form of a segmental gear 25 which intermeshes with the rack-teeth 19. The lower and depending arm of the lever 24 is slightly off-set, as 95 shown in Fig. 4, to bring it closer to a depending slotted arm 24^a rigidly attached to the grate section and provided with an angular slot 24^b. The arm 24 is provided with a slot 26 and an arm 27 projecting at right 100 angles thereto longitudinally of the fire-box, the said arm being formed at its outer extremity with an angular groove 28 which registers with and conforms to the slot 24^b in the arm 24^a.

105 For operating the grate sections and the grate bars carried thereby, we have shown two independent levers 29, one of which is adapted to be alternately connected to either the two forward grate sections or their grate bars, and the other serving to operate the rear section and its grate bars only. (This

arrangement, however, may obviously be modified and a single operating lever employed in connecting all of the grate sections or two grate sections may be in connection with each rod, as will be hereinafter apparent.)

The connection between the grate sections and their grate bars is effected with the operating levers 29 by rods 30 slideable in hangers 10 30^a, and which carry fixed collars 31, two for each grate section, arranged respectively opposite the slot 24^b in the arm 24^a and the slot 26 in the lever 24. These slots are adapted to be alternately engaged by pins 32 carried by the collars 31, the pin 32 opposite the slot 24^b also operating when engaged therewith to engage the groove 28 in the arm 27 thereby preventing any relative movement of the grate bars when the rods 30 are reciprocated. The reciprocation of the rods 20 when engaged with the arms 24^a and 27 causes the grate sections to swing on their pivots to and from a dumping position. When the rods 30 are given an axial turn of ninety 25 degrees the pins 32 in engagement with the arms 24^a and 27 are disengaged therefrom, and the pins 32 opposite the slots 26 are carried thereinto. On now reciprocating the rods 30 the grate sections remain stationary 30 and the grate bars will swing back and forth on their pivots by reason of the sliding movement of the slide 17.

In order to provide for the axial turning of the rods 30 at the outside of the furnace adjacent to the operating levers 29, they are keyed to sleeves 33, the latter being in fixed relation to collars 34 having handles 35 by which the rods 30 are revolved. The outer extremities of the sleeves 33 each pass 35 through a bearing-box 36 formed as a part of one of the levers 29, and is provided with a head 37 which serves in connection with the collar 34 to hold the box 36 in place. Each bearing 36 is preferably pivotally attached 40 to the front of the furnace through the intermediary of connecting links 38 and 39; these links admitting of the levers being moved to and from the furnace in reciprocating the rods 30.

50 While we have described the preferred construction and arrangement of our improved furnace grate, we nevertheless regard the precise embodiment of the invention as material, and consider ourselves entitled to such modifications as fall within the scope of the appended claims.

Having thus described our invention, we claim as new and desire to secure by Letters Patent:

60 1. In a grate, a plurality of pivoted grate sections, a plurality of grate bars pivotally supported on each section, and a single mechanism operable to either swing said sections on their pivots or oscillate the grate bars on 65 the grate sections.

2. In a grate, a plurality of pivoted grate sections, a plurality of grate bars pivotally supported on each section, an operating rod, means for axially revolving said operating rod to alternately connect it to the grate sections and to the grate bars, and means for reciprocating said rod, whereby the grate sections or grate bars with which it is connected will be swung on their pivots. 70

3. In a grate, a pivoted grate section, a plurality of grate bars pivotally supported on said section, an operating rod having engaging devices and means for axially revolving said rod to alternately engage said devices with either the grate section or the 80 grate bars, and means for reciprocating said rod for the purpose described.

4. In a grate, a pivoted grate section, a plurality of grate bars pivotally supported on said section, each having a depending arm 85 provided with a stud, a slide carried by the grate section having slots with which the studs of the grate bars engage, means for reciprocating the slide, whereby the grate bars are caused to oscillate on their pivots, and means partly included in said first-named means for swinging the grate section. 90

5. In a grate, a pivoted grate section, a plurality of grate bars pivotally supported on said section, an operating rod, a device carried by said rod, means for axially revolving the rod to engage said device with the grate section and lock the grate bars thereon against relative movement relative to the grate section, and means for reciprocating 100 the rod, whereby the grate section is carried to and from a dumping position. 95

6. In a grate, a pivoted grate section having a depending slotted arm, grate bars carried by said section, an operating lever, an 105 operating rod connected to said lever, and means carried by said rod adapted to be engaged and disengaged with the slot of said arm when the rod is revolved.

7. In a grate, a plurality of pivotally mounted grate bars having arms provided with studs, a slotted slide in engagement with said studs, rack-teeth formed on said slide, a slotted lever having a segmental gear in engagement with the rack-teeth of the slide, an 110 operating lever, a rod connected to said lever, and means carried by said rod adapted to be engaged and disengaged with the slot of said slotted lever for the purpose described. 115

8. In a grate, a pivoted grate section, a 120 plurality of grate bars pivotally supported on the grate section, a slide carried by the grate section, means connecting the slide with the grate bars, whereby when the slide is reciprocated the grate bars are swung on their 125 pivots, a lever for reciprocating the slide having a depending slotted arm, a depending slotted arm carried by the grate section, a rod, means carried by said rod adapted to alternately engage the slots of said lever and 130

said arm when the rod is axially revolved, and means for reciprocating the rod.

9. In a grate, a pivoted grate section, a plurality of grate bars pivotally supported on said section, studs carried on the inner face of the grate section, a slotted slide carried on the studs, slotted means carried by the slide, depending arms carried by the grate bars having inwardly projecting studs in engagement with the slots of said means, whereby when the slide is reciprocated the grate bars are swung on their pivots, means for reciprocating the slide, and means for swinging the grate section on its pivots.

10 15 10. In a grate, a pivoted grate section, a plurality of grate bars pivotally supported on said section, a slide for swinging the grate bars on their pivots carried by said section, a lever for reciprocating said slide having a 20 depending slotted arm, a grooved arm rigidly connected to the slotted arm, a depending arm rigidly connected to the grate section having a slot in register with the groove of said grooved arm, means adapted to alternately engage the slotted arm of said lever and the registering slot and groove of said last-named arm, and means for reciprocating said means.

11. In a grate, a pivoted grate section, a 30 plurality of grate bars pivotally supported on said section, a slide carried by said grate section and connected with said grate bars, a lever for reciprocating the slide having a depending slotted arm, a depending slotted arm

carried by the grate section, a rod, pins projecting from said rod adapted to alternately engage the slots of said lever and said arm when the rod is axially revolved, and means for reciprocating the rod.

12. In a grate, a pivoted grate section, a 40 plurality of grate bars pivotally supported on said section, a slide carried by the grate section having rack-teeth, means connecting the grate bars and slide together, whereby as the latter is reciprocated the grate bars are 45 swung on their pivots, a lever having a segmental gear in mesh with the rack-teeth of the slide, a reciprocating operating means adapted to be alternately engaged with the lever and the grate section, whereby the 50 grate bars and grate section may be independently swung on their pivots.

In testimony whereof I have signed my name to this specification in the presence of two subscribing witnesses.
